SUPPORT FOR PICTURE FRAMES AND
THE LIKE

William Haverman, West Asheville, N. C.

Application June 2, 1943, Serial No. 489,405

2 Claims. (Cl. 348—36)

The present invention relates to an improved supporting standard or easel for picture frames and the like, the frames being capable of holding photographs, pictures, and other objects of art.

Prior art patents directed to easels are usually rather complicated and expensive to produce, and are not readily removable from the frame after they have been attached thereto. Another disadvantage of prior art easels is that they usually have more than one point of contact with the supporting surface on which the frame is to be placed. These several points of contact together with the points of contact on the bottom of the frame, endanger the frame as it may not be rigidly supported.

It is a mathematical fact that a common plane can be found for any three points, and therefore, my present invention comprehends the use of an extremely simple easel which is cheap to manufacture and which is constructed so that it only has one sharply defined point of contact with its supporting surface when mounted on a frame, the other two points of contact being the frame per se.

Another object of my invention is to provide an easel manufactured from a single blank of wire folded on itself to provide an upstanding leg and diverging at its upper portion to form two arms that are sufficiently resilient for projections thereon to be inserted in suitable openings at the respective sides of a frame.

Other objects and advantages of this invention will be apparent upon consideration of the following detailed description when considered in conjunction with the accompanying drawing, wherein

Figure 1 is a perspective view of the easel removably attached to a picture frame;

Figure 2 is an elevation of the easel shown in Figure 1, and

Figure 3 shows in elevation a modified form of the easel shown in Figure 2.

The easel designated generally at 10 is attached to the picture frame 11 by means of projections 12 inserted in eyelets 13, fastened to the back of the said frame.

The easel itself is formed of rigid steel wire or other suitable material, the leg 14 of which is constructed by bending and doubling the wire for a portion of its length and spot welding or soldering the same at one or more points 15 to render the leg a unitary member having a sharply defined point of contact. The arms 16 form a continuation of the leg and diverge at the top part thereof. The upper portions of the arms

are preferably bent upright forming approximately the same angle with the remainder of the respective arms, as the arms, per se, form with the leg, so that they are generally parallel to the leg 14. In addition, these upper portions are bent back as shown in Figure 1, to form retaining members 17 for the purpose of maintaining the leg in fixed, spaced relationship with the frame when the easel is mounted thereon.

10 The projections 12 are soldered or spot welded to the arms at the points where the retaining members 17 form an angle with the arms 16. The arms 16 are rigid, but sufficiently flexible to permit squeezing the retaining members together far enough to insert the projections in the eyelets 13 of different sized frames, and then the outward spring action of the arms causes the projections to be rigidly inserted and engaged in the eyelets 13.

15 20 The modification disclosed in Figure 3 is similar in design to the easel shown in Figure 2, i. e., they are both generally Y-shaped. However, in this case the easel is constructed by first bending together a wire blank and twisting the same sufficiently to form a leg 18 having diverging arms 19. The ends of the arms are doubled back and twisted to form retaining members 20 with ends 21 projecting at right angles to the retaining members 20. This easel functions in the same manner as that shown in the preferred form.

25 30 It is readily apparent that the design and construction of the easels constituting my invention are simple and cheap to place on the market, so that they have great utility for use in combination with all types of picture frames. The one sharply defined point of contact of the leg effects a rigid support for the frame when it is attached and permits ready positioning of same at any convenient place. Their ease of removal make them particularly adaptable in cases where pictures are to be either placed on household articles or converted to the hanging type where hanging wire can be substituted upon the said removal of the easel.

35 40 45 50 55 What is claimed is:

1. A substantially Y-shaped easel for supporting picture frames and the like comprising a leg and two arms extending outwardly from the top portion thereof, each arm being bent up at its upper end to form a stop means for maintaining the leg in fixed, spaced relationship with the frame when the easel is mounted thereon and each arm having a projection extending therefrom at approximately the point where it is bent, said projections extending in diverging relation-

ship outwardly from said arms, the arms being sufficiently flexible to be urged toward each other whereby the easel may be removably mounted at will on different sized frames by engagement of the projections with suitable openings in said frames.

2. In combination with a picture frame and the like having openings in the back for attaching an easel thereto, a substantially Y-shaped easel comprising a unitary leg member formed of a single blank of wire doubled on itself and twisted together, and two diverging arms forming a continuation of said leg member, the upper end of each arm being doubled on itself and

5 twisted and bent upwardly to form a stop for maintaining the leg in a fixed, angular relationship with the frame when the easel is mounted thereon, and the extreme end of each arm projecting at right angles to said twisted stop member at approximately the point where it is bent, said extreme ends projecting in divergent relationship from said arms, the arms being sufficiently flexible to be urged toward each other 10 whereby the easel may be removably mounted at will on different sized frames by engagement of the said projecting ends with suitable openings in said frames.

WILLIAM HAVERMAN.
